UNITED STATES PATENT OFFICE.

JOSEPH L. BEANE, OF LE GRAND, IOWA.

BOLT-BEARING.

1,160,821.

Specification of Letters Patent.

Patented Nov. 16, 1915.

Application filed November 23, 1912. Serial No. 733,195.

To all whom it may concern:

Be it known that I, JOSEPH L. BEANE, a citizen of the United States, and a resident of Le Grand, in the county of Marshall and State of Iowa, have made certain new and useful Improvements in Bolt-Bearings, of which the following is a specification.

My invention is an improvement in rodless end gates for wagons, and has for its object the provision of mechanism for securing an end gate in place on a wagon, without the use of the usual rod, and wherein the gate may be locked or released without removing the locking means from the gate.

In the drawings: Figure 1 is a perspective view of the rear end of a wagon body provided with the improvement, showing the gate in place and locked; Fig. 2 is a longitudinal vertical section near one of the sides of the body; Fig. 3 is a perspective view of one corner of the body, showing the gate in place but unlocked; and, Fig. 4 is a perspective view of the bearing for one of the locking bolts.

In the present embodiment of the invention, each of the sides 1 of the body of the wagon is provided with a vertical strip 2 secured to the inner face of the side member near the rear end thereof, and the end gate 3 is adapted to rest at its ends against the said strips, the said gate being of such length that it will fit between the sides 1 of the body, and will rest at its lower edge against the bottom 4 of the body. As a rule the end gate is of such width, that the upper edge thereof will be flush with the upper edges of the sides.

A bar or strip 5 is secured to the outer face of the gate near each end thereof, and in spaced relation with respect to the said end, and the said strips extend a little more than half of the width of the gate. The upper end of each of the strips is beveled, as shown at 5^a, and the locking means for the ends of the gate are arranged at the upper ends of the said strips and in alinement therewith. Each of the locking means is as before stated near the upper edge of the gate, and the lower edge is held in place against the strips 2 by means of the angle plates, shown in Fig. 1. Each of the said plates consists of a portion 6 secured to the bottom 4 of the wagon body on the upper face thereof, by means of rivets 7, or the like, and an approximately vertical portion 8, the said portion 8

of each angle plate being inclined outwardly toward its upper end, as shown more particularly in Fig. 2.

Each of the locking or holding devices above mentioned, consists of a bolt or rod 9, having at one end a transverse head or lug 10 and at the other end with an angular handle 11. Each of the said handles is provided intermediate its ends with a lateral bend 13, for convenience in grasping the handle, when the bolt is in locked position.

When the bolt is in locked position, the handle extends downwardly alongside the outer face of the end gate, and alongside the inner edge of the adjacent strip 5. In this position the handle is not liable to be caught by anything to disengage the gate. Each of the bolts 9 is mounted to rotate and to move longitudinally in the bearing shown in Fig. 4. Each of the said bearings consists of two sections, the outer section being composed of a plate 17 having a transverse central recess 18 formed by bending the plate laterally, and the said recess 18 is adapted to receive the bolt 9 and the inner bearing section 14. The inner section 14 has its outer face grooved, as shown, to fit the bolt 9, and the said section is provided at each side edge with a transverse lug 15. The section 17 is provided at each side of the recess 18 with a notch 16 for receiving a lug 15. The recess 18 is of such depth that when the bolt 9 is in place and the inner section 14 has its lugs 15 engaged with the notches 16, the rear face of the said section will be flush with the rear face of the plate.

The ends of the plate 17 are provided with openings 19 for receiving rivets 20, to hold the outer section to the end gate, and the engagement of the lugs 15 with the recesses 16 of the outer section prevents movement of the bearing sections with respect to each other. The bolt 9 is rotatable and slideable in the bearing, and each of the sides 1 of the body is provided with an opening 24^a in alinement with the bolt.

A plate 21 is secured over the opening, each of the plates being of general elliptical form, and secured to the outer face of the side of the body by rivets 22, and each plate has an opening or slot 23 at its center, for permitting the passage of the head 10 of the adjacent bolt. When the head passes through the opening or slot and is turned transverse to the said opening or slot, the

bolt is locked from return movement, thus locking the end gate in place in the body. It will be noted that the slot 23 in the plate 21 is rounded at each side intermediate the ends, to receive the rounded end of the bolt 9.

In operation, with the end gate in place, as shown in Fig. 1, to release the same, it is only necessary to oscillate the bolt into the position shown in Fig. 3, that is in such position 10 that the handle 13 is approximately perpendicular to the face of the end gate. The bolt may now be moved longitudinally, since the head 10 is in alignment with the slot 23. When the bolt is moved longitudinally, the 15 head passes through the opening 23 of the plate 21, and through the opening of the side member 1 of the wagon body, until the said bolt and head is clear of the said member. Now the upper edge of the end gate is 20 free from the body, and the said gate may be lifted upwardly until the lower edge clears the portions 8 of the angle plates, after which the end gate may be moved either upwardly or rearwardly.

25 To replace and lock the end gate, it is positioned against the strips 2, as shown in Fig. 1, with the lower edge between the said strips and the angle plates 6—8. The bolts are now moved longitudinally to cause the 30 heads to pass through the openings 24^a in the sides of the body and through the openings of the plate 21, and the handle is permitted to drop into the position shown in Fig. 1, thus turning the bolt to cause the 35 head 10 to stand at right angles, to the opening 23, thus preventing withdrawal of the bolt.

From an inspection of Figs. 1 and 2, it 40 will be seen that the portion 8 of each of the said angle plates inclines outwardly toward its upper free end, permitting the upper edge of the gate to be moved rearwardly without interference from the said portions 8 of the angle plates. This manner of arranging the said portions 8 also facilitates the placing of the gate in closed position, since the said portions form a guide for guiding the gate into position against the strips.

50 The handle 11 acts as a stop for limiting the longitudinal movement of the bolt 9 in one direction. The length of the said bolt is such that when the said handle 11 is in contact with the end of the bearing for the bolt, the head 10 will be in such position that it 55 may be turned transverse to the slot of the plate 21.

The handle 11 is approximately at right angles to the direction of length of the head 60 10, so that the weight of the handle will tend

to hold the head in locked position, that is transverse to the slot 23.

The outer bearing section 17 is provided at the end adjacent to the end 11 with a notch or recess 24 for receiving the handle 65 11, as shown more particularly in Fig. 3. The bolt 9 is of such length, that when the handle 11 is in the recess 24 of the bearing, the head 10 will extend beyond the outer face of the side 1 of the wagon body a slight 70 distance. When now the handle is moved downward, the bolt is forced longitudinally, as the handle moves out of the notch 24, thus pressing the head tightly against the reinforcing plate 21. The notch acts as a 75 cam to insure that the gate will be held tightly in place.

Each end of the end gate is provided with recesses 25 circular in cross section, and in each recess is arranged an anti-friction roller 80 or washer 26 of rubber or the like, each washer having a central opening for receiving a screw 27 to hold the washer in place. The said washer abuts against the faces of the sides of the wagon body, and other rollers or washers may be inserted in the sides of the body, to bear against the washers 26, to prevent rubbing and noise, and to insure that the gate will be held tightly in place.

It will be understood that the head 10 90 may be arranged at any angle with respect to the handle, for whenever the said head is at an angle with respect to the opening 23, the head will be prevented from being withdrawn through the said opening. 95

I claim:

A bearing for a longitudinally movable and rotatable bolt, comprising inner and outer bearing sections, the outer section having an outwardly offset portion intermediate 100 its ends forming a transverse groove on the opposite face, and provided at its ends with means for permitting the sections to be secured to a fixed support, the groove being of greater depth than the diameter of the bolt 105 to be received, the inner bearing section being shaped to fit within the groove and having in its inner face a groove co-operating with the groove of the outer section to receive the bolt, said outer section having 110 notches and the inner section having lugs for engaging the notches to limit the longitudinal movement of the inner section with respect to the outer section, the inner faces of the outer section and the inner section being 115 flush with each other.
